DESIGN FOR A HANGER OR SIMILAR ARTICLE

Julia Read, New York, N. Y.

Application February 9, 1946, Serial No. 126,416

Term of patent 3½ years

(Cl. D80—8)

To all whom it may concern:

Be it known that I, Julia Read, a citizen of the United States of America, residing in New York city, county of New York, and State of New York, have invented a new, original, and ornamental Design for a Hanger or Similar Article, of which the following is a specification, reference being had to the accompanying drawing, forming part thereof, wherein,

The rear of the hanger or similar article is substantially the same in appearance as the front.

I claim:

The ornamental design for a hanger or similar article, substantially as shown and described.

JULIA READ.
